DESIGN FOR A TONE ARM FOR PHONOGRAFS

Walter Miller, Benton Harbor, Mich.

Application November 7, 1945, Serial No. 123,533

Term of patent 14 years

(Cl. D26—14)

To all whom it may concern:

Be it known that I, Walter Miller, a citizen of the United States, residing at Benton Harbor, in the county of Berrien and State of Michigan, have invented a new, original, and ornamental Design for a Tone Arm for Phonographs, of which the following is a specification, reference being had to the accompanying drawing, forming part thereof.

Fig. 1 is a top plan view of a tone arm for phonographs showing by new design.

Fig. 2 is a side elevational view; and

Fig. 3 is an elevational view of the end portion thereof on the line 3—3, looking in the direction of the arrows.

I claim:

The ornamental design for a tone arm for phonographs, substantially as shown.

WALTER MILLER.
